L. E. SIMMONS

MINING MACHINE

Filed July 21, 1922

UNITED STATES PATENT OFFICE.

LEON E. SIMMONS, OF CLAREMONT, NEW HAMPSHIRE, ASSIGNOR TO SULLIVAN MACHINERY COMPANY, A CORPORATION OF MASSACHUSETTS.

MINING MACHINE.

Application filed July 21, 1922. Serial No. 576,473.

To all whom it may concern:

Be it known that I, LEON E. SIMMONS, a citizen of the United States, residing at Claremont, in the county of Sullivan and State of New Hampshire, have invented certain new and useful Improvements in Mining Machines, of which the following is a full, clear, and exact specification.

My invention relates to mining machines. It has for its object to provide an improved means for retaining a mining machine on a truck, and more particularly an improved and simplified means wherein a part of the mining machine mechanism is used as a part of the retaining means. A further object of my invention is to provide improved retaining means for a mining machine wherein the flexible feeding member of the mining machine may be utilized as a part of the retaining means and connected in such manner as to hold the machine in the desired position upon its truck and yet permit of ready and quick disconnection whenever desired.

In the accompanying drawings I have shown for purposes of illustration one embodiment which my invention may assume in practice.

In these drawings,—

Fig. 1 is a plan view of a mining machine mounted upon its truck and retained thereon in accordance with my improvement.

Fig. 2 is a side elevation of the machine shown in Fig. 1.

In this illustrative construction I have shown a truck 1 of a usual type known as a "mule truck", i. e. a truck adapted to be drawn about a mine by mule power or to be pushed about and not provided with truck propelling mechanism, the same including a rigid frame carried upon suitable wheels and having guiding means adapted to receive and retain a mining machine moved longitudinally of the truck; this machine being herein illustrated at 2 as a machine of the longwall type ordinarily used with such trucks and having at one end the usual flexible feeding mechanism including a feed operating member 3 and a flexible connection acted on thereby and herein in the form of a chain 4, while the opposite end of the machine carries a pivoted cutter bar 5 carrying a usual cutter chain 6.

In my improved construction the flexible feeding member 4 is utilized to hold the ma-

chine 2 in position upon the truck 1 and for this purpose a suitable length of the flexible feeding member is carried from the feed operating member 3 to the front end of the machine. There it is connected to an abutment, herein in the form of a rearwardly opening hook 7, provided on the front end and at one side of the truck 1 and then extended across or over the machine and herein in front of the machine body and above the bar 5, preferably in such manner that it snugly grips a part of the machine, the opposite end of this transversely extending portion being then connected to a chain engaging abutment or hook 8, similar to the hook 7 and located on the opposite side of the truck frame. Attention is also directed to the fact that at the rear end of the truck 1 suitable stop means are provided to cooperate with the forward machine movement limiting means just described and limit the rearward movement of the machine 2 on the truck frame 1, these means herein assuming the form of a transverse connection 9 between the usual upstanding longitudinal flanges on the truck, and being adapted to be engaged by cooperating stop members 10 carried on the rear end of the mining machine 2. It will be noted that as usual the feed chain 4 during the loading of the machine onto the truck engages a suitable chain engaging abutment 11 carried on the rear end of the truck and that this abutment cooperates with the chain engaging abutments 7 and 8 in retaining the machine on the truck.

As a result of my improved construction, it will be noted that it is possible to retain the mining machine in the desired position relative to the truck by exceedingly simple and inexpensive means through utilizing the flexible feeding member of the mining machine as one of the retaining elements, and that at the same time that the retaining means is simplified in such manner as substantially to reduce its cost, a retaining means is provided which is of great strength, permits of considerable variation in position, and enables the operator to connect and disconnect the machine quickly and conveniently.

While I have in this application specifically described one embodiment which my invention may assume in practice, it will be understood that this form of the same is

shown for purposes of illustration and that the invention may be modified and embodied in other forms without departing from its spirit or the scope of the appended claims.

5. What I claim as new and desire to secure by Letters Patent is:

1. In a mining apparatus, a mining machine truck, a mining machine thereon including a flexible feeding member, abutment 10 means on said truck adapted to cooperate with said member during machine movement, and supplemental means for retaining said machine in position on said truck utilizing a length of said flexible feeding member 15 as a retaining element and including a plurality of abutment means engaged thereby.
2. In a mining apparatus, a mining machine truck, a mining machine thereon including a flexible feeding member, abutment 20 means on said truck adapted to cooperate with said member during machine movement, and supplemental means for retaining said machine in position on said truck utilizing a length of said flexible feeding member as a 25 retaining element and including abutment means engaged thereby and disposed on opposite sides of said truck.
3. In a mining apparatus, a mining machine truck, a mining machine thereon including a flexible feed chain, abutment 30 means on said truck adapted to cooperate with said chain during machine movement, and supplemental means for retaining said machine in position on said truck utilizing 35 a length of said flexible feed chain as a retaining element and including chain engaging hooks engaged thereby and disposed on opposite sides of said truck.
4. In a mining apparatus, a mining machine truck having machine movement 40 limiting means at one end thereof, a mining machine thereon including a flexible feeding member, abutment means on said truck adapted to cooperate with said member during machine movement, and supplemental 45 means for retaining said machine in position on said truck and against said first mentioned limiting means utilizing a length of said flexible feeding member as a retaining element and including abutment means engaged thereby and disposed on opposite sides of said truck.
5. In a mining apparatus, a mining machine truck, a mining machine thereon including a longitudinally projecting cutter bar and a flexible feed member, and means for retaining said machine on said truck including means for connecting a length of

said flexible feeding member between points on the opposite sides of said truck and over 60 the inner end of said bar.

6. In a mining apparatus, a mining machine truck, a mining machine slidable thereon including a projecting cutter bar and a flexible feeding member, abutment means 65 with which said flexible member engages in the loading of the machine, and means engagable with the inner end of said bar and cooperating with abutments disposed in the rear of said point of engagement for retaining said machine in position on said truck utilizing said flexible feeding member as a retaining element.

7. In a mining apparatus, a mining machine truck, a mining machine slidable 75 thereon including a flexible feeding member, a machine movement limiting means with which said machine engages, and means disposed adjacent the forward end of said machine and utilizing said flexible feeding member as a retaining element for retaining the same in position on said truck against said machine movement limiting means.

8. In a mining apparatus, a mining machine truck, a mining machine slidable 85 thereon including a flexible feed chain, and means for retaining said machine in position on said truck utilizing said flexible feed chain as a retaining element and including rearwardly opening chain engaging hooks 90 engaged thereby and disposed on opposite sides of said truck.

9. In a mining apparatus, a mining machine truck, a mining machine slidable 95 thereon including a frame and a flexible feeding member, and means for retaining said machine on said truck against movement longitudinally in either direction utilizing said flexible feeding member as a retaining element and including abutments 100 engaged thereby and disposed adjacent the ends of said machine frame.

10. In a mining apparatus, a mining machine truck, a mining machine slidable 105 thereon and including a flexible feed member, and means for retaining said machine in position on said truck utilizing said flexible feed member as a transverse retaining element and including a plurality of holding means disposed on different sides of said truck and simultaneously operative to prevent release of said flexible member upon forward movement of said machine on said truck.

In testimony whereof I affix my signature.
LEON E. SIMMONS.
